SEVERN D. SPRONG, OF NEW YORK, N. Y., ASSIGNOR TO WESTINGHOUSE ELECTRIC & MANUFACTURING COMPANY, A CORPORATION OF PENNSYLVANIA.

REGULATOR SYSTEM.

Application filed February 20, 1922. Serial No. 537,859.

To all whom it may concern:

Be it known that I, SEVERN D. SPRONG, a citizen of the United States, and a resident of New York, in the county of Kings and 5 State of New York, have invented a new and useful Improvement in Regulator Systems, of which the following is a specification.

My invention relates to regulator systems and it has special relation to induction- 10 regulator control systems.

One object of my invention is to provide a control system for an induction regulator which will speed up the operation of the regulator in correcting for voltage variations 15 upon the transmission line to which the same is connected.

Another object of my invention is to provide means for preventing unnecessary operation of the induction regulator.

20 More specifically, my invention comprises providing a damped electromagnet and an undamped electromagnet each controlling co-operating movable contact members and being connected in parallel across the supply 25 circuit.

Heretofore, the control of an induction regulator has been effected by means of a contact-making voltmeter controlling a floating contact device that co-operated with two 30 fixed contact members. The gap between the contact members determined the permissible voltage variation before the induction regulator operated in either direction. The single control electromagnet of the voltmeter 35 was undamped. With such a system, the induction regulator operated frequently to correct for slight voltage changes of short duration. Furthermore, the regulator had a tendency to "hunt" if the setting of the 40 voltmeter was close. That is to say, if the voltmeter was set so that a relatively large variation was necessary to operate the induction regulator, increased voltage variations were permissible on the transmission line 45 within that setting. On the other hand, a close setting of the voltmeter caused operation of the regulator upon every voltage variation, however slight.

The variations encountered and which

need to be corrected for are, first, those due 50 to slow changes of the system from one-half to one volt, and which are not immediately perceptible in its effect upon the machines supplied from the system but need to be corrected for if of continued duration, and 55 second, those more abrupt and wider voltage variations which need to be corrected for as rapidly as possible.

In order to properly correct for both 60 classes of voltage variations, the present invention contemplates providing a sensitively-poised but damped element adjusted with an operating contact gap corresponding to a small amount of voltage, say $\frac{3}{4}$ volt, and second, mounting the co-operating contact members upon poised arms and controlling the operation of the same by a similar electromagnet, energized from the same source, through the co-operation of means 65 which may be so adjusted as not to be responsive to voltage variations less than the full voltage of the gap between the contact members, i. e., $1\frac{1}{2}$ volts.

70 Thus, the functioning of the regulator to promptly correct for variations in voltage 75 of continued duration is accomplished by the first element, which has a relatively slow and small actuating movement, while the correction for the larger and more abrupt variations is accomplished by the 80 second element, which has a relatively fast and large actuating movement. Other voltage variations, such as small variations of short duration, will not cause the operation 85 of the induction regulator, since it is not needed. By eliminating unnecessary operation of the regulator and reducing the liability to hunting action, the period of actual corrective operation of the regulator 90 may be shortened.

95 The accompanying drawing is a diagrammatic illustration of circuits and apparatus embodying my invention.

In the figure, an induction regulator is 95 diagrammatically illustrated at 1, as comprising the usual voltage winding 2 and current winding 3, which are connected in a familiar manner to the supply line indi-

cated by the conductors 4 and 5. A motor for operating the induction regulator is indicated at 6, and is controlled by reversing switches 7 and 8. The reversing switches 7 and 8 are adapted to be selectively energized by a mechanism 9, which comprises electromagnets 11 and 12, a pivoted arm 13, carrying contact member 13a, and co-operating pivoted arms 14 and 15, respectively 10 carrying contact members 14a and 15a.

The electromagnet 11 comprises a core armature 16, pivotally connected to the contact-carrying lever arm 13, and an energizing winding 17. A spring 18 co-operates 15 with the contact lever arm 13, as shown. The electromagnet 11 has a two-way dash-pot mechanism 19 co-operating therewith for a purpose to be hereinafter set forth.

The electromagnet 12 comprises a core 20 armature 21 and an energizing winding 22. The electromagnetic windings 17 and 22 are energized from a voltage transformer 23, connected across the transmission line, so that voltage variations in the transmission 25 line may be indicated upon the magnets 11 and 12 to effect the operation thereof.

The electromagnet 12 controls the movements of a rod 24, which extends through registering slots in the lever arms 14 and 15, 30 and has a spring 25 attached to the free end thereof. Two collars or dogs 26 and 27 are mounted upon the rod 24 between the arms 14 and 15. The arms 14 and 15 are adapted to respectively engage limits or stops 28 and 35 29 whenever they are operated, and to operate against the action of springs 30 and 31, respectively.

In the following description of the operation of the apparatus, it will be assumed, 40 solely by way of example, that the normal operating gap between the contact members corresponds to $\frac{3}{4}$ volt. A distinction is herein made between the "operating" gap and the contact gap at the position of rest, 45 as will be hereinafter pointed out. However, where the term is used in the claims, this distinction is not necessarily intended.

Assume that there is an abrupt voltage 50 variation of one and one-quarter volts upon the supply line 4, 5. The electromagnet 12 will be instantaneously actuated, but neither of the arms 14 and 15 will be moved far enough to effect engagement of the contact members because of the action of the springs 55 30 and 31. Therefore, there will be no operation of the induction regulator to correct for this voltage variation. If the variation is of long enough duration to permit the simultaneously-energized and damped electromagnet 11 to move the contact arm 13 a 60 sufficient distance to engage with either of the co-operating contact arms 14 and 15, the induction regulator will be operated to correct for the variation. It will be understood 65 that the control apparatus is so arranged

that a voltage variation is not permitted to exist for a length of time sufficient to have a damaging effect. Also, it will be noted that the co-operating contact members are moved toward each other during the corrective 70 action.

Next, assume a voltage variation of $\frac{3}{4}$ volt of extended duration. This variation will move the electromagnet 11 and the arm 13 a sufficient distance to engage the appropriate 75 co-operating contact member and cause the regulator to correct for the variation. However, simultaneously, the co-operating contact member 14a or 15a has been moved a very slight distance in a direction towards 80 the contact member 13a. That is to say, in effect, the contact gap corresponds to more than $\frac{3}{4}$ of a volt, probably one volt. On a $\frac{3}{4}$ volt variation, the contact members 14a and 15a are moved just enough to make the 85 effective or "operating" gap correspond to $\frac{3}{4}$ volt. When the regulator has been operated to correct for the assumed variation, the voltage upon the magnets 11 and 12 becomes normal. Immediately the undamped 90 magnet 12 returns and permits the arms 14 and 15 to return to normal position, thus promptly breaking contact to de-energize the motor 6 to preclude overrunning of the regulator. In the above operation, the time element is determined by the setting of the dash-pot mechanism 19.

It will be noted that the regulator has not been operated to correct for the small variation until it has existed for a predetermined 100 length of time, which time is long enough to insure that the variation is more than temporary and, therefore, should be corrected for.

Next, assume an abrupt voltage variation 105 of $1\frac{1}{4}$ volts. The electromagnet 12 will be immediately operated to cause engagement of the appropriate contact members to operate the induction regulator to correct for the voltage variation. Upon the return to normal voltage, the undamped element again permits prompt breaking of contact engagement.

In each of the above instances, it will be understood that the normal operation is that 115 the mechanism 9 selectively energizes the reversing switches 7 and 8 to rotate the motor 6 in the one direction or the other. An increased voltage upon the transformer 23 will lower the core of the electromagnet 11 and 120 raise the core of the electromagnet 12, while a decreased voltage upon the transformer 23 will raise the core of the electromagnet 11 and will lower the core of the electromagnet 12. 125

In the actual construction of the apparatus, the collars 26 and 27 may be adjusted upon the rod 24 in order to give different settings therefor.

By eliminating the unnecessary function- 130

ing of the regulator even with close setting of the contact members of the control apparatus, the tendency of the regulator to overrun is eliminated. It, therefore, has become possible to rearrange the gearing between the motor and the regulator so as to speed up the corrective operation of the regulator.

Modifications in the system and arrangement and location of parts may be made within the spirit and scope of my invention, and such modifications are intended to be covered by the appended claims.

I claim as my invention:—

1. In a regulator system, the combination with a supply circuit and an induction regulator connected thereto, of control means therefor comprising an electromagnet, a contact-carrying arm controlled thereby, time-element mechanism co-operating with said electromagnet, a pair of movably-mounted contact members co-operating with said arm, and a second electromagnet connected in circuit with the first-mentioned electromagnet and adapted to selectively control the operation of the pair of contact members.

2. In a regulator system, the combination with a supply circuit and an induction regulator connected thereto, of control means therefor comprising an electromagnet, contact-making mechanism controlled thereby, a dash-pot mechanism co-operating with said electromagnet, a pair of movably-mounted contact members co-operating with said mechanism, and a second electromagnet adapted to selectively control the operation of the pair of contact members, said electromagnets being operated in accordance with variations in a characteristic of said supply circuit.

3. In a regulator system, the combination with a supply circuit and an induction regulator connected thereto, of control means therefor comprising an electromagnet, contact mechanism controlled thereby, a dash-pot mechanism co-operating with said electromagnet, a pair of movably-mounted contact members co-operating with said mechanism, and a second electromagnet energized to selectively control the operation of the pair of contact members in accordance with variations in a characteristic of said supply circuit, whereby said regulator will function to correct for relatively small continued variations in said supply circuit and relatively large variations in said supply circuit.

4. In a regulator system, the combination with a supply circuit and a regulator connected thereto, of control means therefor comprising a damped electromagnet, a main contact member controlled thereby, a pair of movably-mounted contact members co-operating with said main contact mem-

ber, and an undamped electromagnet adapted to control the operation of the pair of contact members.

5. The combination with a supply circuit and a regulator therefor, of control means for said regulator comprising a relatively slow-acting electromagnet and a relatively fast-acting electromagnet, both electromagnets being energized in accordance with the supply circuit characteristic to be regulated, and co-operating contact mechanism having a pair of contact members controlled by one of said electromagnets.

6. The combination with a supply circuit and a regulator therefor, of control means for said regulator comprising a relatively slow-acting electromagnet, contact means controlled thereby, a relatively fast-acting electromagnet, and a second contact means adapted to be selectively controlled by the operation of the second-mentioned electromagnet, said electromagnets being energized by the same electrical quantity.

7. In a regulator system for a supply circuit, the combination with an induction regulator connected thereto, of control means therefor comprising a reversible motor, switches controlling the direction of rotation of said motor, a relatively slow-acting electromagnet, a contact-carrying arm controlled thereby, a pair of movably mounted contact members co-operating with said arm and a relatively fast-acting electromagnet adapted to control the operation of the pair of contact members to selectively energize said switches, said electromagnets being energized in accordance with the voltage of said supply circuit.

8. The combination with a supply circuit and a regulator therefor, of control means for said regulator comprising contact means having co-operating movable contact members, and a damped element and an undamped element respectively co-operating with said contact means to control the same, to thereby control said regulator, and means for energizing said elements in accordance with variations in the same electrical quantity.

9. The combination with a supply circuit and a regulator therefor, of control means for said regulator comprising contact means having co-operating movable contact members, and a damped actuating element and an undamped actuating element respectively co-operating with said contact members and controlled in accordance with variations in the supply circuit characteristic to be regulated, whereby said regulator will be operated only in the event of a relatively small continued variation and a relatively large variation in the supply-circuit characteristic.

10. The combination with a supply circuit

and a regulator therefor, of control means for said regulator comprising contact means having co-operating movable contact members, and actuating means for said contact members controlled in accordance with variations in the supply-circuit characteristic to be regulated and so arranged that one portion of said contact members will be actuated upon a relatively small variation and another portion of said contact members will be actuated upon a relatively large variation.

11. The combination with a supply circuit and a regulator therefor, of control means for said regulator comprising contact means having co-operating movable contact members, and actuating means respectively co-operating with said contact members and controlled in accordance with the supply-circuit characteristic to be regulated, one of which means has a relatively small corrective movement and the other of which has a relatively large corrective movement.

12. The combination with a supply circuit and a regulator therefor, of control means for said regulator comprising contact means having co-operating movable contact members, and actuating means respectively co-operating with said contact members and controlled in accordance with variations in the supply-circuit characteristic to be regulated, one of which means has a relatively small and slow corrective movement, and the other of which has a relatively large and rapid corrective movement.

13. The combination with a supply circuit and a regulator therefor, of control means for said regulator comprising contact means having co-operating movable contact members, and actuating means respectively co-operating with said contact members and controlled in accordance with variations in the supply-circuit characteristic to be regulated, one of which means has a relatively small and damped corrective movement, and the other of which has a relatively large and undamped corrective movement.

14. In a regulator system, the combination with a supply circuit and an induction regulator connected thereto, of control means therefor comprising an electromagnet, contact-making mechanism controlled thereby, a dash-pot mechanism co-operating with said electromagnet, a pair of movably-mounted contact members co-operating with said mechanism and a second electromagnet adapted to selectively control the operation of the pair of contact members, said electromagnets being operated in accordance with variations in a characteristic of said supply circuit and adapted to move the co-operating contact members toward each other.

15. In a regulator system, the combination with a supply circuit and an induction

regulator connected thereto, of control means therefor comprising an electromagnet, a contact-carrying arm controlled thereby, a dash-pot mechanism co-operating with said electromagnet, a pair of movably-mounted contact members co-operating with said arm, a second electromagnet connected in circuit with the first-mentioned electromagnet and adapted to selectively control the operation of the pair of contact members, and means for preventing hunting action.

16. In a regulator system for a supply circuit, a regulator connected thereto, control means for said regulator comprising a damped electromagnet and an undamped electromagnet, said electromagnets being energized in accordance with the characteristic to be regulated, contact-making mechanism controlled by said electromagnets whereby said regulator will function to correct for relatively small continued variations in said supply circuit and relatively large variations in said supply circuit, and means for preventing hunting action.

17. The combination with a supply circuit and a regulator therefor, of control means for said regulator comprising a relatively slow-acting electromagnet and a relatively fast-acting electromagnet, both electromagnets being energized in accordance with the supply-circuit characteristic to be regulated, and co-operating contact mechanism having a pair of contact members controlled by one of said electromagnets, and means for preventing hunting action.

18. The combination with a supply circuit and an induction regulator connected thereto, of control means therefor comprising a reversible electric motor, a plurality of switches controlling the direction of rotation of said motor, a damped electromagnet, a single undamped electromagnet, contact means controlled by said electromagnets to selectively energize said switches, and means for preventing hunting action.

19. In a regulator system, the combination with a supply circuit and a regulator connected thereto, of control means therefor comprising a damped electromagnet, a main contact member controlled thereby, a pair of movably-mounted contact members co-operating with said main contact member and an undamped electromagnet adapted to control the operation of the pair of contact members, the co-operating contact members being moved toward each other.

20. The combination with a supply circuit and a regulator therefor, of control means for said regulator comprising a relatively slow-acting electromagnet, contact means controlled thereby, a relatively fast-acting electromagnet, and second contact means adapted to be selectively controlled by the operation of the second-mentioned electro-

magnet, the co-operating contact means being adapted to be moved toward each other in the control operation.

21. The combination with a supply circuit and a regulator therefor, of control means for said regulator comprising contact means having co-operating movable contact members, and a damped element and an undamped element respectively co-operating

with said contact members to control the same, to thereby control said regulator, and means for energizing said elements in accordance with variations in the same electrical quantity.

In testimony whereof, I have hereunto subscribed my name this 15th day of February 1922.

SEVERN D. SPRONG.
